UNITED STATES PATENT OFFICE.

CARL STREETER DICKENS, THOMAS EDWIN SCHLEY, AND JOHN WHARTON NEWTON, OF BEAUMONT, TEXAS, ASSIGNEES TO MAGNOLIA PETROLEUM COMPANY, OF DALLAS, TEXAS, A VOLUNTARY JOINT-STOCK ASSOCIATION OF TEXAS.

WAX-SWEATING APPARATUS.

Application filed November 13, 1920. Serial No. 428,869.

To all whom it may concern:

Be it known that we, CARL S. DICKENS, THOMAS E. SCHLEY, and JOHN W. NEWTON, citizens of the United States, residing at

5 Beaumont, in the county of Jefferson and State of Texas, have invented new and useful Improvements in Wax-Sweating Apparatus, of which the following is a specification.

10 This invention relates to an apparatus intended primarily for the fractional separation, by sweating, of crude, slack, intermediate and other types of paraffin-wax and like mixtures of substances having different 15 melting points. The invention has as its object the provision of an apparatus in which may be expeditiously and economically conducted a continuous wax sweating process as above described.

20 Another object of the invention is the provision of an apparatus which is adaptable to the sweating of all types of paraffin-wax without in any way modifying the structure of the apparatus.

25 In its broad aspect the invention contemplates the provision of a chamber divided into a plurality of compartments, each compartment having heating means which may be regulated to bring the temperature of the

30 compartment to a desired predetermined degree. The wax is conducted through the chamber upon an endless, foraminous belt beneath which, in such compartment, are located oil receiving receptacles to receive the 35 oil from the melted wax.

The invention also contemplates the provision of an improved means for charging the apparatus so that the wax will be placed upon the belt evenly and uniformly.

40 Other features and objects of the invention, such as a provision of means for readily determining the temperature within each of the compartments and means for preventing the passage of heat from one 45 compartment to the other, will become obvious from a reading of the following detail description in connection with the accompanying drawings, wherein there is shown one specific form which our invention may 50 take.

In these drawings:

Fig. 1 is a longitudinal sectional view of one end of the apparatus,

Fig. 1^a is a similar view of the other end of the apparatus.

55

Fig. 2 is a horizontal sectional view on the line 2—2 of Figs. 1 and 1^a, the central portion of the apparatus being shown as broken away for lack of space.

Fig. 3 is a transverse section on the line 3—3 of Fig. 1.

Fig. 4 is a detail view showing the feed roll drive.

Fig. 5 is another detail view showing the manner of connecting the chain to the belt, 65 and

Fig. 6 is a detail view showing the construction of the chain links.

Referring to the drawings more in detail, 10 indicates a sweating chamber constructed of concrete, brick or other suitable material and supported upon longitudinally extending beams 11 and transverse beams 12, which beams, together with the vertical supports 13, afford a foundation for the sweating chamber. The chamber is divided by means of partitions 14 into a plurality of compartments 10^a, 10^b, 10^c, 10^d, etc., it being understood that the chamber may be of any desired size and may contain any given 80 number of compartments.

Each partition 14 has an opening 15 through which extend a plurality of parallel tracks 17 extending through all of the compartments from one end of the chamber to the other and serving to support an endless belt 18 constructed preferably of perforated steel plates. The belt 18 travels through the openings in the partitions forming the several compartments and also traverses drums 19 and 20 at the front and rear ends, respectively, of the chamber. The edges of the belt are supported by means of idler pulleys 21 rotatably mounted in depending brackets 22 supported from the girders 23 embodied in the ceiling construction of the chamber.

The specific character of the belt will be hereinafter referred to more in detail for it is thought well, at this point, to refer to the fact that each of the compartments is provided with an entrance opening 24 in which is located a closure 25 thus permitting access to each of the compartments for inspection and repair of the apparatus.

Within the compartments are placed oil 105 receptacles 26 the receptacles being, of

course, located beneath the wax carrying belt, and deflectors 27 being provided adjacent each edge of the several receptacles to direct the falling oil to the pans. The oil 5 may be removed from the pans either by drain pipes which connect with each of the receptacles, or the individual receptacles, or the individual receptacles may be removed when they become filled. The receptacles or 10 pans 26 may be supported upon longitudinally extending beams 28 below which beams may be located the heating means for the individual compartments. In the form of the device illustrated the heating means is 15 shown as being steam containing coils 29, several coils being provided for each compartment. If desired, a thermostatic valve 30 may be located adjacent each compartment so that the heat therein may be readily 20 regulated to the desired degree. These valves may be manually regulated or, as shown in the drawings, may be automatically operated by means of a heat responsive element 30^a located in each compartment, it 25 being understood that any suitable type of thermostatic valve may be used for this purpose. Above each compartment are located thermometers 31 projecting into each compartment so that the heat in the latter may 30 be determined without entering the compartment.

By an inspection of Figs. 1 and 1^a it will be observed that adjacent the openings 14 in the several partitions and to the latter 35 are secured flexible curtains 32. The lower edges of these curtains rest upon the surface of the traveling belt, thus effectually closing the openings above the belt to the 40 passage of the heat from one chamber to the other.

From the description of the sweating chamber thus far given it will be noted that the construction is such that any desired degree may be maintained in the compartments severally and collectively, that means is provided for quickly determining the temperature within each of the compartments, and that quick inspection of any given compartment may be made by reason 45 of the provision of the entrance openings in the sides of the compartments.

Referring to the construction of the endless belt, any suitable material, such as wire mesh, may be used, but the construction 50 shown in the drawings has been found to be preferable, the illustrated construction comprising a plurality of comparatively narrow perforated metal plates 33 extending transversely of the belt and held together edge 55 to edge by means of a pair of endless chains 34 secured to the under face of the belt adjacent its lateral edges. By reference to Figs. 5 and 6 it will be noted that the chains are formed from a plurality of links, each 60 link being provided with a pair of laterally

extending ears 36 having openings therein through which are passed bolts 37 extending through the belt plates 33 and thus rigidly securing the chains to the plates. Each of the links is also formed with an 70 end hook 38 which engages the adjacent link in the manner indicated in Fig. 6.

The wax carrying belt traverses pulleys 19 and 20 at the forward and rear ends of the machine, these drums or pulleys having 75 secured thereto at each end sprockets 39 which mesh with the chains upon the traveling belt.

Any suitable means may be used to charge the belt, but in the illustrated embodiment 80 of the invention there is shown a roller 40 mounted above the drum 19 in bearings 41 suitably positioned above and at each end of a wax pan 42, the pan and the roller 40 being so related that the periphery of the 85 roller extends into the pan. At one side of the roller is located a scraper 43 which, upon rotation of the roller, removes the wax from the roll and permits it to gravitate upon the endless belt.

Power may be applied to the cold wax supplying roller 40 from a motor or any other suitable source of power 44 (Fig. 4), the power being transmitted therefrom through a short shaft 45 having a pulley 46 90 traversed by a chain 47 which also traverses a pulley 48 fixedly secured to a shaft 49. Upon the shaft 49, which has bearings 50 at one end of the charging roll, is fixedly secured a worm 51 meshing with a worm gear 52 secured to the axle 53 of the charging roll. In order that there may be a fixed 95 relation between the movement of the traveling belt and the charging roll, power may be transmitted from the latter to the drum 100 19 by means of a sprocket 54 (Fig. 2) upon the end of the charging roll shaft through chain 55 and sprocket 56 upon the shaft of the drum 19.

The charging roll and drum 19 may both 110 be mounted in a chamber 57 at the forward end of the apparatus, and this chamber may be provided with a closure 58 through which admittance may be obtained to the chamber to inspect the working of the charging 115 apparatus.

Wax may be supplied to the pan 42 through a supply line 60 which leads to the pan from a reservoir 61 at the rear end of the apparatus, and the wax in the pan may 120 be maintained in a fluid state by means of a heating coil 62 located in or designed to the pan.

In operation it will be understood that wax is conducted from the reservoir 61 to 125 the pan beneath the charging roll where it is maintained in a substantially fluid state. Rotation of the charging roll, which is cold, will cause the roll to pick up upon its periphery a quantity of wax at each revolution. 130

Wax will be removed from the roll by the scraper 43 and will gravitate upon the slowly moving belt, to be conducted through the several compartments of the sweating chamber, which are heated in varied degrees, the wax being subjected to higher degrees of temperature as it passes through the chamber. Each of these compartments is heated by the coils positioned therein, the last compartment 10° being substantially larger than the remaining compartment, and being heated to substantially the same degree as the compartment 10°. As the wax passes through each chamber its various fractions, which are susceptible to melting at the temperatures maintained, will drip into the receiving pans through the perforations in the belt. Wax may be removed from the pans in any manner, either by attaching a drain pipe, or by removing the pans at intervals, admission being obtained to the compartments for this purpose by means of the various entrances shown therein.

It is, of course, to be understood that numerous modifications may be made in the apparatus herein described in detail, and that these modifications may be made without in any way departing from the spirit or scope of the invention, which is more particularly defined in the following claims.

What is claimed is:

1. An apparatus for sweating paraffin and the like, comprising an elongated closed sweating chamber having a plurality of compartments situated end to end in a substantially horizontal plane, partitions in said chamber separating said compartments, an endless foraminous belt having a substantially horizontal path of travel through said compartment, means for heating each of said compartments to varying predetermined degrees, oil receiving receptacles in said compartments beneath said belt, a supply chamber at one end of said sweating chamber, means in said supply chamber for continuously depositing wax upon said belt, and means for moving said belt through its path of travel.

2. An apparatus for sweating paraffin and the like comprising an elongated closed sweating chamber having a plurality of interior partitions forming a plurality of compartments in said chamber, each of said partitions having an opening therein, an endless foraminous belt having a path of travel through said compartments, said belt passing through the openings in said partitions, means associated with said openings whereby the passage of heat between said compartments is prevented, heating coils in each of said compartments for heating the compartments to varying predetermined degrees, oil receiving receptacles in the compartments beneath said belt, a supply chamber at one end of said sweating chamber, means in said supply chamber for continuously depositing wax upon said belt, and means for moving said belt through its path of travel.

ber at one end of said sweating chamber, means in said supply chamber for continuously depositing wax upon said belt, and means for moving said belt through its path of travel.

3. An apparatus for sweating paraffin or the like comprising an elongated closed sweating chamber, a plurality of partitions in said chamber, each partition having an opening therein, a supply chamber at one end of said sweating chamber, an endless foraminous belt having a substantially horizontal path of travel through said compartments and supply chamber and passing through the openings in said partitions, means for heating each of said compartments to varying predetermined degrees, oil receiving receptacles in said compartments beneath said belt, each of said compartments and said supply chamber having an entrance opening, a wax pan in said supply chamber, a cold roll above said pan and said belt, said roller being positioned so that a portion of its periphery is at all times in said pan, means for rotating said roller, means for removing the wax from said roller whereby the wax may fall upon said belt, and means for moving said belt through its path of travel.

4. An apparatus for sweating paraffin or the like comprising an elongated closed sweating chamber, a plurality of partitions in said chamber, each partition having an opening therein, a supply chamber at one end of said sweating chamber, an endless foraminous belt having a substantially horizontal path of travel through said compartments and supply chamber and passing through the openings in said partitions, means for heating each of said compartments to varying predetermined degrees, oil receiving receptacles in said compartments beneath said belt, each of said compartments and said supply chamber having an entrance opening, closures for said openings, a wax pan in said supply chamber, means for supplying wax to said pan, means for heating the wax in said pan, a cold roll above said pan and said belt, said roller being positioned so that a portion of its periphery is at all times in said pan, means for rotating said roller, means for removing the wax from said rolls whereby the wax may fall upon said belt, and means for moving said belt through its path of travel.

5. An apparatus for sweating wax and the like comprising a closed elongated sweating chamber, partitions in said chamber forming a plurality of compartments situated end to end in a substantially horizontal plane, each of said partitions having an opening therein, a supply chamber at one end of said sweating chamber, heating coils in each of said compartments, oil receiving receptacles in said compartments beneath said belt, a supply chamber at one end of said sweating chamber, means in said supply chamber for continuously depositing wax upon said belt, and means for moving said belt through its path of travel.

ments, an endless foraminous belt extending in a substantially horizontal plane through said sweating chamber compartment, tracks extending through said sweating chamber 5 and supporting said belt, a wax pan in said supply chamber, a rotating roller positioned above said pan and having a portion thereof at all times in said wax pan, means for supplying wax to said pan, means for rotating

said roller, a scraper for removing the wax 10 from said roller and permitting it to gravitate upon said belt, and means for moving said belt.

In testimony whereof we have hereunto set our hands.

CARL STREETER DICKENS.

THOMAS EDWIN SCHLEY.

JOHN WHARTON NEWTON.
